VISUAL OIL GAGE OR THE LIKE

Richard A. Thorud, Minneapolis, Minn., assignor to Toro
Manufacturing Corporation, Minneapolis, Minn.

Filed Dec. 28, 1970, Ser. No. 26,666

Term of patent 14 years

Int. Cl. D10—05

U.S. Cl. D52—6

FIG. 1

FIG. 5

FIG. 2

FIG. 6

FIG. 3

FIG. 7

FIG. 4

FIG. 8

FIG. 1 is a perspective view of a visual oil gage or the like showing my new design;

FIG. 2 is a top plan view thereof;

FIG. 3 is a bottom plan view of FIG. 2;

FIG. 4 is a front end elevational view of FIG. 2;

FIG. 5 is a rear end elevational view of FIG. 2; and

FIG. 6 is a left side elevational view of FIG. 2;

FIG. 7 is a right side elevational view of FIG. 2;

FIG. 8 is a front perspective view of FIG. 1, wherein the spout is shown in the closed position.

I claim:

The ornamental design for a visual oil gage or the like, substantially as shown.
